PAPER SHEET DISPENSER

Zevi Moskovitz, 30 Haporzim St., Jerusalem, Israel

Filed Aug. 9, 1965, Ser. No. 86,509

Term of patent 7 years

(Cl. D52—2)

FIG. 1 is a front perspective view of a paper sheet dispenser showing my new design; and

FIG. 2 is a rear perspective view of the paper sheet dispenser of FIG. 1.

I claim:

The ornamental design for a paper sheet dispenser, as shown.
